UNITED STATES PATENT OFFICE.

ALBERT D. RAY, OF CLEVELAND, OHIO.

MULTIPLE TOOL-MACHINE.

1,084,231.

Specification of Letters Patent.

Patented Jan. 13, 1914.

Application filed November 8, 1912. Serial No. 730,122.

To all whom it may concern:

Be it known that I, ALBERT D. RAY, a citizen of the United States, residing at Cleveland, in the county of Cuyahoga and State 5 of Ohio, have invented certain new and useful Improvements in Multiple Tool-Machines, of which the following is a specification.

My invention relates to improvements in 10 multiple tool machines, the primary object of the invention being to provide a multiple or combination tool machine in which a number of machines or machine tools are arranged and combined in a novel manner and provided with means whereby the various parts 15 may be readily transposed and arranged to coöperate with each other in a single combination machine, the present embodiment of the improved multiple or combination machine 20 being particularly designed and adapted for use in small machine shops, automobile garages, and by automobile owners, and the like. For example,—in the present embodiment of the improved multiple or combination 25 machine, the following machine tools or devices are provided, to wit:—a forge, anvil, vise, pipe-vise, emery wheel, drill, lathe, shaper, hack-saw, and milling machine.

30 In carrying out my invention I provide a combination machine in which a number of machines are combined and operated on a single bed plate and by the construction of the various parts of certain machines necessary 35 for use in certain classes of work, such parts are also arranged to form coöoperating parts of other machines performing other kinds of work. By combining these various machines and parts and causing the parts of 40 one machine to take the place of the parts of other machines, the cost of manufacture is greatly decreased and the amount of space required for such machine is reduced to a minimum. Furthermore, owing to the decrease 45 in weight, the improved combination machine is portable and can be moved or carried to the work in hand, and furthermore, by this combination of the various machines above referred to in close proximity to each other the performance of the various 50 kinds of work is facilitated.

With the above mentioned and other ends in view, the invention consists in the novel construction, arrangement, and combination 55 of parts, hereinafter described, illustrated in some of its embodiments in the accompany-

ing drawings, and particularly pointed out in the appended claims.

Referring to the drawings, forming a part of this specification, Figure 1, is a side elevation of the improved multiple machine, the parts being arranged and equipped for use as a hack-saw and mounted on a tool pedestal or cabinet, one of the doors of the latter being open and a portion of the walls 55 being broken away for the purpose of clearer illustration of the parts. Fig. 2, a similar view of the machine, the gear casing and head-stock being provided with a superposed detachably mounted shaper. Fig. 3, a similar view of the same equipped with a slide rest and milling attachment. Fig. 4, a similar view of the same, the mandrel or spindle being equipped with an emery-wheel, and the bed plate with an adjustable support or rest for use in conjunction with said emery-wheel. Fig. 5, a similar view of the same equipped for use as a lathe. Fig. 6, a cross sectional view taken on line 6—6 of Fig. 5. Fig. 7, a perspective view of the movable 60 tail-stock, showing the arrangement of the jaw holding lug and removable interchangeable jaw block, and locking device for the latter. Fig. 8, a top plan view of the removable pivotally mounted forge pan and 65 the adjacent portion of the machine bed, the dotted lines showing the air or draft ducts and the manner in which the forge pan may be turned to one side to cut off the draft of air leading to the latter. Fig. 9, a side elevation of the hack-saw attachment in operation. Fig. 10, a rear or edge view of the same. Fig. 11, a perspective view of the cross head or slide for use in connection with the slide rest as shown, for example, in Fig. 70 3. Fig. 12, a detail top plan, partly in section, of the improved shaper attachment shown in use in Fig. 2, a portion of the walls being broken away for the purpose of clearer illustration of the parts. Fig. 13, a longitudinal sectional view taken on line 13—13 of Fig. 12. Fig. 14, a cross sectional view taken on line 14—14 of Fig. 13. Fig. 15, a longitudinal sectional view through the gear housing or head-stock. Fig. 16, a cross 100 sectional view of the same. Fig. 17, an enlarged sectional view of the fan and fan casing, and showing the gear connections on the live spindle or shaft. Fig. 18, a cross sectional view through the fan casing. Fig. 19, a horizontal sectional view through the gear housing or head-stock. Fig. 20, a per-

spective view of the base or pivoted portion of the forge pan.

Similar numerals of reference designate like parts throughout all the figures of the drawings.

The improved machine comprises a base or bed plate 1, which may be mounted on a pedestal or tool cabinet 2, or other suitable and convenient means of support, and is provided with a combined gear or head-stock 3, at one end, and a combined anvil and tail-stock 4, at the other.

The head and tail-stocks 3, and 4, may be mounted in a suitable way 1^a, of the bed plate, and, in the present instance, are removably mounted therein by means of a side guide member 5, a portion of which is offset at one side and forms a stationary rack 5^a. The guide member 5, and rack portion 5^a, thereof may be secured by means of screws 5^b, as illustrated in Fig. 16, of the drawings.

The head-stock is preferably clamped or otherwise secured in a stationary position and the anvil or tail-stock 4, is adapted to be moved in the guide-way of the bed plate toward and from the head-stock by means of a large vise or lead-screw 6, the latter being mounted in the lower portion of the head-stock 3, and being provided with a hand wheel 7, and handle 7^a.

The head and tail-stocks 3, and 4, are each provided with overhanging jaw portions 3^a, and 4^a, respectively, and with jaw holding lugs 8, adapted to receive removably mounted interchangeable jaw blocks 9, the latter being provided with like sides and having lug receiving openings 9^a, to receive the jaw holding lugs 8, when the jaw or vise blocks 9, are mounted in position, as illustrated in Figs. 1, 2, 6, 7, and 9, of the drawings. As is shown, the removable jaw or vise blocks are adapted to project over the jaw portions 3^a, and 4^a, of the head and tail-stocks, and are provided with vertical and horizontally extending V-shaped notches or grooves 9^b, and 9^c, as well as several half-rounds 9^d, or other suitable and convenient recesses for receiving and containing the work being operated upon such as pipes 50 and bars, as illustrated, for example, in Figs. 1 and 9 of the drawings.

As a means for locking the jaw blocks in seated position upon the lugs 8, the head and tail-stocks 3, and 4, are provided at their sides with key members 10, said key members extending through the lugs 8, and terminating at the rear sides of the latter, and being provided with flattened angular portions 10^a, extending flush with or in a plane with the adjacent side of the lug as illustrated in Fig. 7, and the upper right-hand portion of Fig. 5, so that the jaw blocks 9, may be readily slipped upon or removed from the holding lugs, and when it is desired to lock the blocks 9, in position,

said key members are rotated in an opposite direction or to the positions shown in the other figures of the drawings through the medium of the handles 10^b, whereby the rounded portions of the tip of the key members opposite the flattened portions 10^a, will be projected from the lugs 8, and into the key receiving recess 9^e, of the adjacent sides of the jaw blocks, as shown most clearly in Fig. 6, of the drawings.

The spindle 11, extends through the gear housing or head-stock and at one end is provided with a loosely mounted fan 12, arranged within a fan casing 13, bolted upon the rear end of the gear housing or head-stock. As a means for bringing the live spindle 11, into engagement with the fan 12, when it is desired to operate the fan as a blower, the projecting end of the spindle is provided with a clutch member or knob 14, having a bayonet slot 14^a, to receive a pin extending from the spindle 11, and operated in an obvious manner whereby a pin or projection 15, on the clutch member will be seated in an opening 15^a, in the hub portion of the fan when the clutch member is twisted to released position and is thrown into engagement with the hub portion of the fan by the operation of the spring 16, as illustrated most clearly in Fig. 17, of the drawings.

The live spindle 11, is provided at its end with a tapered socket opening 11^a, and an exteriorly threaded collared head 11^b.

As a means for driving the spindle 11, as well as giving the same a changeable or low and high speed, the spindle 11, is provided with a tight bevel gear 17, meshing with a second bevel gear 18, on a driving shaft 19, the latter being adapted to be driven, in the present instance, by means of a crank wheel 20, and crank 20^a, so that when the two gears 17, and 18, are in mesh, as shown in Fig. 19, a slow speed for the spindle 11, will be provided upon the revolution of the crank 20^a, and driving shaft 19.

As a means for changing to high speed the shaft 19 is adapted to be shifted longitudinally by first lifting the lock lever 21, out of the annular groove 19^a, in the driving shaft, and thereupon shifting the driving shaft inwardly whereby the bevel gear 18, is thrown out of mesh with the bevel 17, and the larger bevel gear 22, will be brought into mesh with the beveled portion of the compound gear 23, loosely mounted on the spindle 11. Upon such shifting the lock lever 21, is dropped into the outer or adjacent annular groove 19^a, and the spur gear portions of the gear 23, meshing with a pinion 24, on a shaft 25, will cause the latter, through the medium of a large gear 26, near the opposite end and meshing with a pinion 27, on the spindle 11, to give the latter a very high speed in an obvious man-

ner where such high speed is desired, as for example, in operating the fan 12, hereinbefore referred to, or an emery wheel, as illustrated in Fig. 4, of the drawings.

5 As a means for conveniently locating and operating a hack-saw 28, as shown in Figs. 1, 9, and 10, of the drawings, one end of the driving shaft 19, is provided with a threaded portion 19^b, and a collar 19^c, on 10 the side of the gear housing or head-stock opposite the crank 20^a, said threaded portion 19^b, being adapted to carry a crank disk 29, having a threaded hub 29^a, said hub 29^a, having an annular guide groove 15 29^b, for receiving and containing the slotted base or handle portion 28^a, of the hack-saw, the latter being adapted to be reciprocated through the medium of a connecting link 30, and the length of the stroke of the hack-saw may be regulated by changing the position of the bearing screw or bolt 31, with 20 respect to the center of the crank disk 29, and for which the different bolt receiving openings 29^c, are provided in the crank disk.

25 By reason of the above construction it is obvious that the improved hack-saw may be readily attached or detached, as desired.

The anvil or tail-stock 4, is provided with a flaring opening 4^b, to receive and contain 30 a tapered tail center pin 32.

When it is desired to use the machine as a milling machine, as shown in Fig. 3, an arbor or driving spindle 33, with an internally threaded head 33^a, is attached to the 35 threaded head 11^b, of the live spindle, the opposite end of the arbor 33, being supported by means of the tail center pin 32, and the milling cutter 34, mounted thereon by means of collars 35, in a well known and understood manner.

40 When it is desired to operate a grinding, buffing, or polishing wheel, such for example, as an emery wheel 36, the latter may be mounted upon the arbor 33, in lieu of the milling cutter 34, as illustrated in 45 Fig. 4, of the drawings, in which instance an adjustable support or rest 37, may be provided, as shown.

The carriage 38, is slidably mounted upon 50 the bed plate 1, and is adapted to receive its motion through the crank wheel 39, extending in front of the apron portion 38^a, of the carriage, the crank wheel 39, operating a spur gear 40, through the medium of a 55 pinion 41, whereby the engagement of the spur gear 40, beneath the rack portion 5^a, of the guide member 5, will cause the carriage 38, to be moved as desired. The carriage is provided with a guide member 38^b, for the 60 cross slide 42, the latter being adapted to be operated by means of a feed screw 43, and a handle 43^a. The cross slide is provided with a suitable tool rest 44, and a suitable tool holder 45, for carrying the tool 46, when 65 used as a lathe, as shown in Figs. 5 and 6,

of the drawings, in which instance, the work or material being operated upon is supported at one end by means of a suitable clamping dog 47, connected to a face plate 48, in a well known and understood manner.

75 When it is desired to use the machine as a milling machine, as shown in Fig. 3, or for analogous purposes, a special work holder or milling attachment such as shown in Fig. 11 of the drawings may be substituted upon the carriage in lieu of the cross slide 42, and tool rest 44, shown in Figs. 5 and 6 of the drawings, said work holder comprising a cross slide or shoe member 49, supporting a lateral supporting head 49^a, 80 having an inclined guide member 49^b, the latter supporting a slidably mounted horizontally arranged shelf 50, said shelf or support 50, being adapted to be adjusted by means of a feed screw or rod 51, having 85 a handle 51^a. The horizontal support or shelf 50, is provided with a guide member 50^a, carrying vise jaws or clamping members 52, and movable by means of a feed screw or rod 53, having a handle 53^a.

90 As a means of providing a forge attachment, the base or bed plate 1, is provided with an opening or duct 54, (see Figs. 15, 16, and 18) communicating with the fan casing 13, at one end and communicating at the 95 other end with a detachable pivotally mounted forge pan 55, the latter being provided at its base with a disk shaped bearing head 55^a, adapted to be pivotally connected and supported by means of a pivot bolt 56, said 100 forge pan having an air duct 55^b, normally communicating with the duct 54, when the forge pan is in its normal position, as shown in Fig. 8, said forge pan being adapted to be moved horizontally on its pivot to the 105 position indicated by the dotted lines in said figure of the drawings whereby the air duct 55^b, in the base of the forge pan is brought out of communication with the opening or duct 54, in the bed plate 1, as may be desired.

110 The shaper attachment comprises a supporting base plate 57, adapted to be mounted upon and secured to the top of the gear housing or head-stock 3, by means of an 115 opening 57^a, at its front and adapted to receive and fit over the jaw holding lug 8, and secured at its rear by means of screw bolts 58, as shown in Fig. 13, of the drawings. The base 57, is provided with a guide member 57^b, having undercut sides as shown, to 120 form a guide for the transverse or cross slide 59.

125 The cross slide is provided with suitable guide members 60, for the reception of the longitudinally movable ram 61, and as a means for operating the ram 61, as well as regulating the length of its stroke, the cross slide 59, is provided with a supporting portion or bearing 59^a, carrying a horizontally 130

disposed crank bevel gear 62, the latter being provided with a bearing bolt 62^a, and having an adjusting slot 62^b, provided with an adjustable bearing member 63, the latter being 5 provided with a bearing screw bolt 64, connecting one end of the connecting link 65, the opposite end of said connecting link being secured to the ram 61, by means of an adjustable bolt and nut 66, adjustably 10 mounted in a longitudinal bearing slot or guide-way 67, said adjusting bolt 66, and bearing slot 67, enabling the ram to be adjusted longitudinally with respect to the position of the work in hand while the adjustment of the adjusting bolt 62^a in the slot 62^b of the crank gear 62, enables the length of the stroke of the ram to be regulated as desired.

As a means for driving the crank gear 62, 20 a small bevel gear or pinion 68 is provided, the latter having a bearing stud shaft 68^a, mounted within a bearing sleeve or member 59^b, of the cross slide 59.

As a means for operating the bevel gear 25 pinion 68, the shaft 68^a, thereof is provided with a longitudinal opening adapted to receive a driving shaft 69, provided with a feather 70, said driving shaft being supported at one end by means of a bracket bearing 30 71, and the driving shaft 69, may be operated by moving the hand wheel 20, and handle 20^a, from the shaft 19, below and connecting it to the driving shaft 69, as illustrated in Fig. 2, of the drawings. The 35 forward end of the ram may be provided with any suitable and convenient tool holding head 72, and tool 73, together with suitable adjusting feeding mechanism.

The cross slide 59, is adapted to be fed 40 by means of a cross slide feed screw 74, carried in brackets 75, of the supporting base and connected to a lug 59^c, at the rear of the cross slide, said cross slide feed screw 74, being adapted to receive its motion by 45 means of a ratchet head 76, and a short reciprocating arm 77, carrying a pawl 78, said arm 77, being adapted to be reciprocated by means of a connecting link or arm 79, having a bearing head 79^a, mounted on an 50 eccentric member 80, carried by the driving shaft 69.

From the foregoing description, taken in connection with the accompanying drawings, the operation and advantages of my invention 55 will be readily understood.

Having thus described some of the embodiments of my invention, what I claim and desire to secure by Letters Patent is,—

1. A multiple tool machine, comprising a 60 bed, head and tail-stocks, two-speed gearing within said head-stock, a spindle adapted to be operated thereby and adapted to support a tool or work-piece in conjunction with said tail-stock, a longitudinally movable driving shaft transversely mounted in said 65

head-stock and adapted to be shifted to operate said gearing at different speeds, means for holding said driving shaft in its respective shifted positions, a carriage in co-operative relation to said spindle, means for connecting and adjusting said tail-stock, and means for moving said carriage. 70

2. In a multiple tool machine, a bed, head and tail-stocks mounted thereon and each provided with a jaw holding lug, interchangeable jaw blocks mounted on and projecting beyond said head and tail-stocks and provided with openings receiving said jaw holding lugs, and key members for locking said jaw-blocks in engagement with said jaw 80 holding lugs. 75

3. A multiple tool machine, comprising a bed, head and tail-stocks mounted thereon, clamping means removably mounted on said head and tail-stocks, a spindle mounted in 85 said head-stock, two-speed gearing in said head-stock, a tool adapted to be driven by said gearing, a longitudinally movable driving shaft mounted transversely in said head-stock and adapted to operate said gearing 90 at different speeds when shifted to its respective positions, a carriage mounted on said bed between said head and tail-stocks, means for connecting and adjusting said head and tail-stocks, and means for moving 95 said carriage.

4. In a multiple tool machine, head and tail-stocks provided at their top with jaw holding lugs, jaw blocks having openings removably receiving and containing said 100 jaw holding lugs and provided with key receiving recesses, and key members extending from the sides of said head and tail-stocks and intersecting certain of the sides of said jaw holding lugs, said key members being 105 adapted to be projected into and out of said key receiving recesses of said jaw blocks by the rotation of said key members.

5. In a multiple tool machine, the combination of a head-stock and a tail-stock, a 110 driving shaft and gearing carried by the head-stock, and a tool driven by said gearing, of clamping means removably held on said head-stock and tail-stock, respectively, and adapted to clamp work to be operated 115 on by said tool, a spindle driven by said gearing and adapted to co-operate with the tail-stock to support a tool or work-piece, and a carriage adjustable longitudinally of the machine and adapted to support a work-piece or tool to co-operate, respectively, with the tool or work-piece carried by said spindle. 120

6. In a multiple tool machine, a bed, head and tail-stocks mounted thereon, a driving 125 shaft and gearing carried by said head-stock, a tool driven by said gearing, clamping means carried by said head and tail stocks and adapted to support the work to be operated on by said tool, a spindle driven 130

by said gearing and adapted to coöperate with said tail-stock to support a tool or work-piece, and a carriage adjustable longitudinally on said bed and adapted to support a work-piece or tool in coöperative relation with the tool or work-piece, respectively, carried by said spindle.

7. In a multiple tool machine, a bed, head and tail-stocks mounted thereon, means for moving said tail-stock in clamping relation to said head-stock, a driving shaft and gearing carried by said head-stock, a spindle driven by said gearing and adapted to co-

operate with said tail-stock to support a tool or work-piece, and a carriage adjustable 15 longitudinally on said bed and adapted to support a work-piece or tool in coöperative relation, respectively, with the tool or work-piece carried by said spindle.

In testimony whereof I have affixed my 20 signature in presence of two witnesses.

ALBERT D. RAY.
